Primary Examiner — Doris Clark(74) *Attorney, Agent, or Firm* — David A. Burge(57) **CLAIM**

I claim the ornamental design for a utility trench side panel portion, substantially as shown and described.

DESCRIPTION

FIG. 1 is a front perspective view showing a first embodiment of my new design, with broken line indicating indefinite height;

FIG. 2 is a rear perspective view thereof;

FIG. 3 is a rear view thereof;

FIG. 4 is a top view thereof;

FIG. 5 is a bottom view thereof;

FIG. 6 is a left end view thereof, it being understood that a right end view is a mirror image of the left end view;

FIG. 7 is a front perspective view showing a second embodiment of my new design which differs from the first embodiment in that broken lines indicate indefinite length;

FIG. 8 is a rear perspective view thereof;

FIG. 9 is a rear view thereof;

FIG. 10 is a top view thereof;

FIG. 11 is a bottom view thereof; and,

FIG. 12 is a left end view thereof, it being understood that a right end view is a mirror image of the left end view.

Broken lines and subject matter depicted thereby are provided for illustrative purposes, and form no part of the claimed design.
